ATTORNEY

UNITED STATES PATENT OFFICE

NINO BELLOCCHIO, OF NEW YORK, N. Y.

FIRE EXTINGUISHER

Application filed December 31, 1928. Serial No. 329,502.

This invention relates generally to fire extinguishers and has more particular reference to a novel manual operable fire extinguisher.

5 The invention has for an object the provision of a device of the class mentioned, which is of simple durable construction, desirable in use and efficient in action, and which can be manufactured and sold at a reasonable cost.

10 The invention proposes the use of a bottle provided with a stopper thru which a metallic tube passes. A valve is arranged on the top of this tube and connects with a nozzle 15 and a head for depressing the tube. Said head is arranged on the top of the valve body. The lower end of the tube is provided with a vial breaking foot normally resting against a vial filled with citric acid. The tube may 20 be manually depressed for causing the breaking of the vial and the citric acid within which coacts with a solution of sodium bicarbonate contained in the bottle so as to raise a pressure within the bottle and cause 25 a discharge of its contents.

A portion of the tube within the stopper may be formed with a reduced tapered portion coactable against a tapered portion of the stopper for forming a tight joint when 30 the tube is in a depressed condition. This arrangement reduces the frictional resistances between the stopper and the tube permitting easy depression of the tube. A means 35 may be provided for holding the tube in its depressed condition for insuring a gas tight joint between the stopper and the tube when the pressure within the bottle rises due to the chemical reaction.

40 The present application shows a further development of the invention disclosed in my pending application, filed August 24, 1928, Serial No. 301,868.

45 For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:—

Fig. 1 is a plan view of a device constructed according to this invention.

Fig. 2 is a vertical sectional view thereof. 55

Fig. 3 is a sectional view, taken on the line 3—3 of Fig. 2.

Fig. 4 is a sectional view, taken on the line 4—4 of Fig. 3.

Fig. 5 is an enlarged view of a portion of 60 Fig. 2.

The reference numeral 10 indicates generally a bottle of any design or construction preferably made of metal and provided with a neck 11 having threads 12. A cap 13 threadedly engages upon the threads 12 for closing the top of the bottle. In addition, a stopper 14 is engaged within the neck of the bottle. A metallic tube 15 passes thru an aperture 16 formed in the cap 12 and thru an aperture 17 formed in the stopper. A collar 18 is fixed upon the tube 15 beneath the stopper 14 for preventing excessive upward motion of the tube. 65 70 75

The tube 15 is of L-shape and the bottom portion 19 thereof is provided with a plurality of slots 20 for providing a passage from the interior of the bottle thru the tube. A vial breaking foot 21 is attached upon the tube 15 and engages against a vial 22 filled with citric acid 23. The vial breaking foot 21 is composed of two sections secured together. 80

The top of the tube 15 is formed with a valve body 24 and a valve 25 is arranged within this body. A stem 26 connects on the valve body and is provided with a head 27. The lower portion of the valve body 24 has a shoulder 28 which coacts with the top of the cap 13 for limiting the downward motion of the tube 15. A nozzle 29 connects with the valve 25 so that in open condition of the valve a passage exists between the nozzle and the tube 15. 85 90 95

The stopper 14 has a tapered aperture portion 17'. The tube 15 is provided with a tapered portion 15' coactable with the tapered portion 17' of the stopper for providing a tight joint when the tube 15 is in a depressed condition. This arrangement re- 100

duces the frictional area between the stopper and the tube so that a much smaller force is necessary to depress the tube than if the contacting area between the stopper and the tube were greater.

5 A pin 30 projects from the shoulder 28 and is aligned with an aperture 31 formed in the cap 13 and another aperture 32 formed in the stopper 14. A stationary arm 33 is embedded within the stopper and is connected with a pivotal link 34 having a pivotal locking pin 35 on its free end. This locking pin 35 extends into a transverse aperture 36 communicating with the opening in the stopper 14. A string 37 connects with the pivotal joint between the locking pin 35 and the link 34 so that upon pulling the string the locking pin 35 may be moved into an inoperative position as shown in the drawing.

10 The tube 15 is provided with a recess 38 arranged for receiving the locking pin 35 when the tube is in its depressed condition. Upon depression of the tube 15 the pin 30 enters the apertures 31 and 32 and acts 15 against the locking pin 35 for moving the locking pin inwards into the recess 38 and thus holding the tube 15 in its depressed condition. The tube cannot be raised until the string 37 is drawn upon for retracting the 20 locking pin from its locking position.

25 In operation of the device the vial 22 is broken by manually striking the head 27 for depressing the tube. Upon a breaking of the vial 22 citric acid within the vial is free and 30 chemically reacts with a solution of sodium bicarbonate 39 held within the bottle 10. Gases are then released which raises the pressure within the bottle and causes its contents to pass thru the slots 20 and thru the tube 15 35 and finally out of the nozzle 29. This discharge may be directed against a flame of a fire for extinguishing it. The nozzle 29 may be turned for operating the valve 25 and cutting off the discharge if this is desired.

40 45 While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

50 55 1. In a fire extinguisher, a stopper for closing a bottle with a solution of bicarbonate of soda and formed with an aperture, a tube slidably engaging in the aperture for breaking when depressed a vial holding citric acid 60 within the bottle and for directing the discharge from the bottle, a pin connected with the tube and extending within an opening in the stopper upon depression of the tube, pivotally connected links mounted in the opening in the stopper and extendible by said

pin for engaging in a recess in the tube and holding the latter element depressed, and a string connected with the links and extending from the stopper for manual drawing to disengage the links from the tube.

70 2. In a fire extinguisher, a stopper for closing a bottle with a solution of bicarbonate of soda and formed with an aperture, a tube slidably engaging in the aperture for breaking when depressed a vial holding citric acid within the bottle and for directing the discharge from the bottle, a pin connected with the tube and extending within an opening in the stopper upon depression of the tube, pivotally connected links mounted in the opening in the stopper and extendible by said pin for engaging in a recess in the tube and holding the latter element depressed, and manual operable means for disengaging the links from the tube.

75 80 85 In testimony whereof I have affixed my signature.
